3 Sheets-Sheet 2

A technical line drawing of a valve assembly, labeled FIG. V. The top part shows a circular valve body with a textured outer ring and a central circular opening. The bottom part shows a vertical assembly with a cylindrical base labeled 24, a rectangular component labeled 25, and a top section with a valve stem and packing labeled 26. Various numbers (23, 24, 25, 26, 27, 28, 29, 30, 31, 32, 33, 34, 35, 36, 37, 38, 39, 40, 41, 42, 43) are used to label specific parts and features of the valve.

IRONING MACHINE

Wayne Myers, Benton Harbor, Mich.

Application February 9, 1932, Serial No. 591,765

3 Claims. (Cl. 68—9)

My invention relates to the type of ironing machines commonly known as flat work ironers which are used for ironing such laundered articles as bed sheets, table cloths and the like.

- 5 An object of my invention is to create a machine that will be much less expensive to construct, less expensive to transport and less expensive to maintain than machines of other design having a like capacity.
- 10 Another object of the invention is the provision of improved means for holding the work against the ironing cylinder and for transporting the work through the machine.

These objects I attain by the use of the new 15 and novel mechanism illustrated in the accompanying drawings, in which—

Figure 1 is a side elevation of my machine with part of side frame broken away to show gears. Fig. 2 is a plan view. Fig. 3 is a section 20 on the line A—A of Fig. 2 in the direction of the arrows. Fig. 4 is a section on the line B—B of Fig. 2 showing a housing around the end of a drive roller, 6. Fig. 5 is a section on the line V—V of Figure 2.

25 Similar numerals refer to similar parts in both views.

1 is a side frame. 2 is a cylinder which is journaled on trunnions 3 and 3a. Trunnion 3 is provided with a steam joint 4 which is fitted 30 with a supply pipe 4a, leading to a suitable steam supply and with a siphon pipe 4b which leads to a point inside the cylinder near the lower portion of the arc, and a drain pipe 4c leading to a steam trap in the usual manner. 5 is a 35 conveyor belt of wire cloth which is wrapped around the cylinder 2 and rollers 6, 7, 8, 9 and 10 and over roller 11. The provision of this fine mesh wire cloth results in a machine of superior operation, producing work of superior 40 quality. This results from the fact that in the use of a machine of this character, in which the cylinders are usually of sufficient length to take a full sized bed sheet lengthwise of the sheet, a miscellaneous assortment of pieces are frequently passed through the ironer. In other words, the material passing through does not always extend the full length of the cylinder so that during a part of the ironing operation there are two and sometimes three and four operators spaced along the feeding side of the machine, each passing small articles into the cylinder. As a result, one section of the cylinder may be receiving thin light articles, such as handkerchiefs, whereas another section of the 45 machine may be receiving heavy wet articles

such as towels, small blankets and the like. In view of the fact that none of this material is dry, being passed into the ironer directly from the washing process, there is a wide difference in the moisture content of the articles. The 5 belt, therefore, stretches differently across its width so that there may be a sag or loose part in the center due to excessive moisture at this point. In this loose area the work will not be pressed against the cylinder with the same force 10 as in other parts of the belt, thus resulting in a lack of uniformity in the type of work performed by the machine. However, the applicant has found that by the use of a woven wire conveyer, instead of the usual canvas conveyer, 15 this difficulty is entirely eliminated since the wire will stretch uniformly throughout its width regardless of the amount of localized moisture, the moisture furthermore being transmitted through the conveyer and out of the ironing zone 20 as soon as it is converted into steam. Another new result accomplished by the use of the woven wire conveyer is the longer life of the conveyer and ironing element.

Rollers 6, 7, 8, 9, and 11 are journaled in bearings 12, 13, 14, 15, and 16 which are carried on the side frames. Roller 10 is journaled in the side frame.

Bearings 12, 13, 14 and 15 are movable in the side frames. Bearings 14 and 15 are adjusted 30 by means of the adjusting screws 18 and 19. Bearing 13 is held in position by spring 17. Bearing 12 floats in its guides adjusting itself to any ordinary variation in thickness of material being ironed.

35 Gear 20 is attached to the trunnion 3a and has a pitch diameter equal to the diameter of the cylinder. Gear 20 is driven by pinion 21 which is secured to shaft 22. Roller 6, which I have called a suction roller because of the fact 40 that air is drawn into the same, and V-belt sheave 23 are also secured to shaft 22.

24 is an electric motor and 25 is a reduction gear which drives shaft 26. The V-belt sheave 45 27 is secured to shaft 26. 28 is a V-belt which drives the machine.

29 is a series of feeding tapes which serve to deliver the work to the cylinder. These feeding tapes pass around the roller 30 and the rod 31. Roller 30 is secured to a shaft 32 which is journaled in bearings 33 which are adjustable by means of adjusting screw 34 in the side frames. Rod 31 is secured in the side frames.

A sprocket 35 is secured to the shaft 32 and 55

another sprocket 36 of the same pitch is secured to the shaft 22. A chain 37, corresponding to the pitch of said sprockets 35 and 36 is passed around them and connected in the usual manner.

5 A suction box 43 extends along the roller 6 and houses the end of the hollow drive roller 6, said end being perforated by a plurality of openings 44a. The pipe 41 connects said housing to the 10 exhaust fan 42. Roller 6 is further perforated by a plurality of openings 44.

15 45 shows a series of guide fingers which separate the feed ribbon and aid in the delivery of the work to the cylinder. Said guide fingers are carried on the rod 31.

16 46 is the delivery table to which the work is delivered by the conveyor 5.

20 Pinion 21 has a pitch diameter somewhat larger than the diameter of the suction roller 6, which 25 results in driving the cylinder 2 a little faster than the conveyor 5.

25 The sprockets 35 and 36 are proportioned to drive the feeding tapes 29 at a speed slightly 30 slower than that of the belt 5, to help remove wrinkles before coming in contact with cylinder 2.

30 The mode of operation is as follows: The motor 24 is started. The cylinder 2, the conveyor 5 and the feeding tapes 29 move in the direction 35 indicated by the arrows on Fig. 1. The various rollers are adjusted to give the proper tension to the conveyor.

35 The exhaust fan 42 is started and a current of air moves through the perforations in suction 40 roller 6 into suction box 43. The air current proceeds through the piping system to the exhaust fan 42 and from thence to the outer air.

40 Flat laundered material which has been conditioned for ironing is spread on the feeding 45 tapes. The material is delivered over the fingers 45 onto the conveyor 5 just before it contacts with the cylinder 2. From this point the material is held in close contact with the hot surface of the cylinder. As the damp material is brought into 45 contact with the heated surface of the cylinder, most of the moisture is quickly evaporated and the resulting vapor readily passes through the interstices of the wire screen cloth. Ironing is

accomplished by the difference in speed between the cylinder and the conveyor.

5 When the material reaches the roller 6, the suction, created by the movement of air through the holes 44, and thence to the fan 42, holds the 10 material to the conveyor so that it is pulled away from the surface of the cylinder and carried over the top of said roller. From this point it is carried by the conveyor to the table 46.

15 I anticipate many possible modifications of the 10 form shown, within the scope of my invention which I conceive to be the system of holding the material to be ironed against the surface of a heated chamber by means of a metal conveyor of a flexible and porous construction and preferably, removing said material from the surface 15 of said chamber by suction thru said conveyor.

Having described my invention, I claim—

1. An ironing machine, comprising the combination of a cylinder; means for heating the surface of said cylinder; a conveyor of foraminous material passed around a portion of the circumference of said cylinder; means for feeding material between the surface of said cylinder and said conveyor; means for imparting motion to 20 said conveyor and to said cylinder; means for removing said material from the surface of said cylinder by suction thru said conveyor.

2. An ironing machine, comprising in combination with a heating cylinder; a conveyor of 25 foraminous material passed around a portion of the surface of said cylinder; means for feeding material between said conveyor and the surface of said cylinder; means for imparting motion to 30 said conveyor and to said cylinder; and a suction roll for removing said material from the 35 surface of said cylinder positioned to draw the material away from the cylinder by pneumatic action through the conveyor.

3. An ironing machine comprising in combination 40 a heated rotated ironing cylinder, a conveyor of foraminous material passed around a portion of said cylinder for pressing the material to be ironed against the surface of the cylinder, and means for removing said material from the 45 surface of the cylinder by suction through the conveyor.

WAYNE MYERS.
